Max Berkowitz, Lawrence, N. Y.

Application December 1, 1939, Serial No. 88,597

To all whom it may concern:

Be it known that I, Max Berkowitz, a citizen of the United States of America, residing in Lawrence, Long Island, county of Nassau, and State of New York, have invented a new, original, and ornamental Design for a Handbag, of which the following is a specification, reference being had to the accompanying drawings, forming part thereof, wherein,

Figure 1 is a front perspective view of a handbag showing my new design.

The characteristic feature of applicant's design resides in the extended portions of the outer fabric carried above the sides of the bag and folding flexibly over and covering the top thereof substantially as shown.

I claim:

The ornamental design for a handbag, substantially as shown, and described.

MAX BERKOWITZ.
